Attorney*

UNITED STATES PATENT OFFICE.

WILLIAM B. ARNOLD, OF NORTH ABINGTON, MASSACHUSETTS; ABBIE L. ARNOLD
AND J. BUTLER STUDLEY EXECUTORS OF SAID WILLIAM B. ARNOLD, DECEASED.

WELT FOR BOOTS AND SHOES.

1,357,677.

Specification of Letters Patent. Patented Nov. 2, 1920.

Application filed April 1, 1919. Serial No. 286,722.

To all whom it may concern:

Be it known that I, WILLIAM B. ARNOLD, a citizen of the United States, residing at North Abington, county of Plymouth, and 5 State of Massachusetts, have invented an Improvement in Welts for Boots and Shoes, of which the following description, in connection with the accompanying drawings, is a specification, like characters on the drawings representing like parts.

The invention to be hereinafter described relates to welts for boots and shoes as an article of manufacture.

In curving a welt around the toe of a boot or shoe, heretofore considerable difficulty and objection have been experienced because of the tendency of the body of the welt to bulge or deform and depart from its ideal flat condition. One of the objects of 20 the present invention, therefore, is to so form the inner edge portion of the welt that the body of the welt may readily be bent or curved as required without substantial deformation from flat condition.

25 In presenting the welt to the upper, it is customary laterally to bend the inner edge portion of the welt at an angle to the body of the welt, in order that the stitching for securing the welt to the upper and inner sole 30 of the boot or shoe may emerge through the grain face of the welt, and that a substantial thickness of leather may serve securely to hold the stitching and prevent the latter from tearing through the welt. Another 35 object of the invention is to so form the inner edge portion of the welt, that it may readily be bent laterally for the purpose set forth.

The grain face of leather is impervious to 40 water while the flesh face readily absorbs water. Heretofore a portion of the grain face nearest the inner edge of the welt has been skived off to facilitate application of the welt to the shoe. As a consequence, a 45 portion of the grain face is lost where it is most needed to prevent water from leaking into the shoe. Another object of the invention is to provide a welt which is readily conformable to the shoe, but retains the 50 grain face portion, which has been heretofore skived off, thereby materially contributing to water tight construction.

In carrying the invention into practical effect, in the present instance, the inner edge

of the welt is provided with a relatively 55 small pliability promoting longitudinal groove extending the length of the welt, the construction being such that transverse and longitudinal flexion of the welt is facilitated, but without objectionably weakening 60 the welt.

The character of the invention may be best understood by reference to the following description of one good form thereof shown in the accompanying drawing, wherein:

Figure 1 is a vertical transverse section through a boot or shoe having a welt embodying the invention;

Fig. 2 on an enlarged scale is a sectional view of the upper and insole and a welt embodying the invention connected thereto by stitching;

Fig. 3 is a view similar to Fig. 2 showing the appearance of the parts after the trimming operation;

Fig. 4 is a transverse section through the welt before the stitching anchoring channel and the pliability promoting groove are formed therein;

Fig. 5 is a transverse section through the welt after the stitching anchoring channel and the pliability promoting groove are formed therein; and

Fig. 6 on an enlarged scale is an isometric view of the welt.

Referring more particularly to the drawing, the welt shown therein as one good form of the invention may be of leather or other suitable material and of any length desired 90 as an article of manufacture. This welt comprises a body 1 having a flesh face 3, an opposed grain face 5, an outer edge 7 and an inner edge 9, said edges being beveled substantially as shown.

The welt may have a suitable shoulder or means for anchoring the stitching thereto. In the present instance of the invention, it is provided with a channel 11 (Figs. 5 and 6) 100 extending longitudinally thereof adjacent the inner edge of the welt and having a wall 13 which desirably may be parallel or nearly parallel to the inner beveled edge of the welt, and having a wall 15 which desirably may be curved or inclined toward and to meet the wall 13.

To promote pliability of the welt, the inner edge portion thereof may have a groove

extending longitudinally thereof, in the present instance, a groove 17 being provided in the inner beveled edge, relatively small as compared to the width of said edge and extending a slight distance into the body of the welt. Preferably this groove 17 is located near to the grain face of the welt to leave a substantial amount of welt material between the groove and the line of juncture 10 of the beveled edge with the flesh face of the welt.

A welt thus formed has a thin lip 19 extending longitudinally thereof adjacent the grain face of the welt, and a thicker, differently shaped lip 21 located intermediate the stitching anchoring channel and the groove, and extending longitudinally of the welt.

In applying the welt to a boot or shoe, 20 the inner edge portion thereof may be bent laterally so that a portion of its grain face will rest against the upper 23, as indicated in Fig. 2. The upper 23 and its lining 25 may be confined between the welt and the 25 shoulder 27 of the inner sole, and the parts may be secured together by stitching 29 anchored in the stitching receiving channel 11 of the welt and in the stitching receiving channel 31 of the inner sole 30.

30 When the welt is bent laterally as described, the lip 21 will be bent to bring the wall 13 of the stitching receiving channel toward and preferably to the wall 15 of said channel, and the lip 19 will be bent toward and into engagement with the lip 21, substantially as shown in Fig. 2. When the welt is thus bent, the groove 17 will be moved out of the line of pull of the stitching 29 out to the plane of the flesh face of 40 the welt, and a substantial thickness of welt stock will be between the bottom of the channel 11 and the adjacent face of the upper, effectively to resist tearing of the threads from the welt.

45 As stated, in curving the welt around the toe of a boot or shoe, there is a tendency for the welt to bulge or deform and depart from its ideal flat condition. The groove 17 desirably promotes the flexibility of the 50 welt and enables the same readily to be bent or curved as required without substantial deformation from flat condition. This flexibility is obtained by the lip 19 and is contributed to by the lip 21 interposed between 55 the lip 19 and the stitching receiving channel 11. When said lips have bent laterally so that they assume their positions shown in Fig. 2, the curving of the welt in the plane of the body thereof, curves the lips 19 and 21 transversely thereof, and since these 60 lips are relatively thin, they readily respond to the curving operation and do not objectionably cramp or congest and interfere with the curving of the remainder of the 65 body of the welt. The beveled outer and

inner edges of the welt also tend to facilitate curving of the welt in the plane of the body thereof, and therefore, the beveled edges combined with the stitching receiving channel and the pliability promoting groove 70 combine to contribute to the production of a highly desirable flexibility, but without loss of strength in resisting tearing of the stitching from the welt.

The construction described has a further 75 advantage in great reduction if not entire elimination of welt stock to be removed in the trimming operation. In Fig. 3 the condition of the welt is represented after the trimming operation, and it will be noted 80 that very little welt stock has been removed, and if the trimming occurred in a plane somewhat farther outward, no welt stock would be removed.

After the welt has been secured to the 85 upper and inner sole by the stitching as described, the outer sole 33 may be presented thereto and secured by lines of stitching 35 passing through the welt and the outer sole in the usual manner. The outer edge of 90 the welt and the outer edge of the sole may be trimmed by the rough rounder into approximate shape, the amount of material taken off varying to suit the type or style of shoe.

95 By my invention is provided a strong, efficient welt which is rendered readily pliable or flexible to permit the welt easily to be flexed about or applied to the shoe without bulging or deforming the welt, and therefore, materially contributes toward the production of a perfect product.

Also the portion of the grain face of the welt adjacent the inner edge thereof is retained so that a wide portion of the grain 105 face is available for contact with the upper, thereby materially contributing to watertight construction.

110 It will be understood that the invention is not limited to the specific embodiment shown, but that various deviations may be made therefrom without departing from the spirit and scope of the appended claims.

What is claimed is:—

115 1. A welt for boots and shoes, comprising a body having opposed faces and inner and outer edges, the inner edge being provided with a longitudinal groove relatively small as compared to the width of said inner edge, to increase the flexibility of the welt transversely to and in the plane of the welt and thereby facilitate application thereof to a 120 boot or shoe, said groove lying entirely to one side of the stitching securing the welt to the upper.

125 2. A welt for boots and shoes, comprising a body having grain and flesh faces and inner and outer edges, a stitch receiving channel in the flesh face of the welt, and a relatively small longitudinal groove in the in- 130

ner edge near the grain face and movable from the line of pull of the stitching out to the plane of the flesh face on lateral flexion of the inner edge to position for application 5 to a boot or shoe.

3. A welt for boots and shoes, comprising a body having grain and flesh faces, an inner beveled edge and an outer edge, and a relatively small groove in the inner beveled 10 edge extending parallel to a face of the welt for increasing the transverse and longitudinal pliability of the welt.

4. A welt for boots and shoes, comprising a body having inner and outer edges, and a 15 pair of longitudinal grooves in the inner edge portion of the welt, one of said grooves being adapted to form a shoulder for anchoring the stitching for securing the welt to the upper and inner sole of a boot or shoe, 20 and the other groove being smaller than the stitching receiving groove and adapted to

promote flexion of the welt in the plane of the body thereof.

5. A welt for boots and shoes, comprising a body having opposed faces and inner and outer beveled edges, a stitching receiving groove in one of said faces, and a relatively small flexion promoting groove in the inner beveled edge adjacent the other face.

6. A welt for boots and shoes, comprising a body having grain and flesh faces and inner and outer edges, the inner edge having a relatively small longitudinal groove extending parallel to a face of the welt for increasing the transverse and longitudinal 35 pliability of the welt, said groove lying entirely to one side of the stitching securing the welt to the upper.

In testimony whereof, I have signed my name to this specification.

WILLIAM B. ARNOLD.
